CLIP BROOCH

Wilhelm Goetz, Providence, R. I., assignor to
Albert Weiner, Providence, R. I.

Application May 10, 1938, Serial No. 206,983

4 Claims. (Cl. 63—20)

The present invention relates to jewelry and it particularly relates to a clip brooch or pin clip combination which may be utilized either in the form of a brooch or in the form of two or more clips.

In the copending applications Serial No. 42,726, filed September 30, 1935, and Serial No. 89,725, filed July 9, 1936, which have now become Patent No. 2,120,215 and Patent No. 2,198,558, respectively there is disclosed a clip brooch combination in which the clips are mounted upon an H-shaped frame structure or upon a structure which is slotted or recessed for resiliency and/or to receive the ornament or jaw members of the usual type of clip or clasp.

It is among the objects of the present invention to provide a novel structure of the character above described in which there will be an additional resilient and/or frictional engagement between the supporting or mounting frame and the clips or clasps or the ornament members thereof, and, which, at the same time, may be readily dismantled into two clips and a frame or assembled into a brooch by the wearer without difficulty.

Another object is to provide an improved clip brooch or pin clip combination of the character above described in which the clips and frame may be repeatedly dismantled to form separate clips or assembled to form a brooch without tendency for the assembly to loosen with wear or upon handling, and in which the frame will be of particularly light construction without sacrificing the rigidity and strength of the assembly and with assurance that the assembly may be readily used as a brooch and the pin may be utilized without interference with the clips or frame and with assurance that the clip brooch will properly hang itself when attached to a dress or to another article of apparel.

Other objects will be obvious or will appear during the course of the following specification.

In accomplishing the above objects, it has been found most suitable according to one embodiment to combine the recessed or slotted frame with the clips, clasps or ornament members in such a manner that there will be a double resilient and/or frictional engagement tending to retain the clips in position upon the frame.

In case of an H-frame, a portion of the ornament or clip is preferably inserted between the legs of the H, while the ends of the legs of the H are preferably compressed between projections on the back of the ornament member or

teeth or other elements forming part of the jaw member of the clasp.

At the same time the frame is preferably provided with a protuberance at the end thereof which will rigidly hold the frame or ornament, clip or clasp together in the assembled brooch structure.

Where the frame is of H-contour, the middle bar of the H is preferably bent away or offset from the plane of the frame so as to latch over projecting portions of the ornament or clip structure.

When all four of the legs are caused to extend in the same direction from a mounting bar, the elevated or offset portions may be provided between each pair of legs to engage similar bosses or enlargements on the back of the clips.

In the case of an H-frame, the pin and catch are preferably mounted upon a parallel extra leg structure, while in the case of an E-bar structure, the pin is preferably mounted upon the connecting element or the bar.

In the drawing, which illustrates several of the various possible embodiments of the present invention, but to which the present invention is by no means restricted, said drawing being by way of illustration and not by way of limitation, since many changes and alterations could be made, all within the scope of the present invention,

Fig. 1 is a rear view of a clip brooch combination showing part of the jaw member of one of the clips broken away to more clearly show the assembly,

Fig. 2 is a longitudinal sectional view upon the line 2—2 of Fig. 1 upon an enlarged scale as compared to Fig. 1,

Figs. 3 and 4, respectively, are transverse sectional views upon the lines 3—3 and 4—4 of Fig. 1 upon an enlarged scale as compared to Fig. 1,

Fig. 5 is a perspective view of the inside face of the jaw member dismantled from the clip,

Fig. 6 is a top perspective view of the H-frame structure, which may be utilized in the assembly of Figs. 1 to 4,

Fig. 7 is a side perspective view of an alternative E-frame structure, which may be utilized in lieu of the H-frame structure of Figs. 1 to 6,

Fig. 8 is a rear view of a clip brooch assemblage including the E-frame structure of Fig. 7.

Referring to the embodiments of Figs. 1 to 6, the two clips A, are mounted back to back upon the clip frame B, which carries the pin and catch combination C. On the back of the clips

are attached the clip findings, including the jaw members D.

In Figs. 1, 3 and 4, the brooch is shown reversed in upside down position and from the rear 5 so as to more clearly illustrate the construction.

Referring particularly to Figs. 2, 3 and 4, the ornaments A may be formed of white metal castings 10 having a plurality of perforations 11 and a plurality of recesses 12 in which are set various stones 13, 14 and 15. The ends of the ornaments 10 are so constructed at 16, that they will closely abut each other.

The ornaments A, as shown, have hollow inside faces 17 and are curved outwardly and downwardly as indicated at 18 to cover the jaw members D. As shown the ornament members are provided with the bosses 19 having the rearward pads or extensions 20, the side flanges 21 and the upstanding post members or back flanges 20 22, said post members, together with said side flange members forming partial boxes at the rear of the ornament adjacent the abutting faces 16.

Extending through the walls or flanges 21 are 25 the pivot pins 23, the ends of which are embraced by or received in the coiled or turned over portions 24 in the ends of the arms 25 of the jaw members D.

Between the arms 25 of the jaw members D is 30 a resilient tongue 26 having a reinforcing embossment 27. The tongue 26 rides over the back wall 22 to lie upon the top of the back wall 22, when the jaw members D are down, as indicated in Fig. 2, or upon the back face 30 of said wall 35 22 when the jaw members are turned upwardly at 90° from the position shown in Figs. 1 to 4.

The jaw members D are provided with the dress or garment engaging teeth 28, which are formed when the slots 29 are made and which extend 40 downwardly from the forward ends of the slots 29. There are also the special slotted engaging teeth 31. These teeth are turned downwardly from the side edges of the jaw member D, as best indicated in Fig. 4, and are turned inwardly adjacent their lower ends, as indicated at 32, the slot 33 affording resiliency.

These teeth 31, tend to exert a resilient grasp on mounting frame or base frame B, pressing the resilient legs of said frame upwardly and inwardly 50 to assure a firm substantial rigid engagement between the clips A and the frame B.

Referring to the frame, as best shown in Fig. 6, there is a central looped or offset bridge 34 forming the cross bar of the H which fits closely over 55 and engages the projections 20 on the ornament and there are also provided the substantially parallel legs 35 and 36 and the auxiliary legs 37, which form a mount for the pin and catch C. The pin 38 is provided with a pivotal mount 39 upon one of said arms 37 and with a detachable catch 40 on the other arm 37.

The enlargements 41 at the outside edges of the legs 35 assure a better rigid connection.

The legs 35 and 36 may also be recessed and slotted, if desired, and it is also possible in certain instances to make the main slots 42 of different sizes to receive the teeth of jaw member D of the clip brooch.

In assemblage the legs 35 and 36 may be inserted into the slideways 43 between the coil portions 24 of the jaw members D and the inside faces 17 of the end of the ornament.

This may be done without manipulation of the jaw members D and with the jaw members down 75 in the position indicated in Figs. 1 and 2. As the

leg members are inserted into the guideways or slideways 43 on the back of the ornament member formed by the elements 24 of the clip finding, they will engage or contact the inside faces of the teeth 31 and the lower bosses of the teeth will tend to 5 press the ends of the frame D upwardly curving them toward the jaw members D as shown in Fig. 2.

When the connection is completed the cam enlargements 41 will snap past the teeth 31, as best 10 shown in Fig. 1, and the loop element 34 will snap onto and over the bosses 20 forming a rigid clip brooch or pin clip construction which will not rattle or loosen and which may be readily attached to a garment by manipulation of the pin 15 and catch C without difficulty or interference with the clip findings or frame.

The action of the legs 35 and 36, in first being spread by the bosses 19 and then pressed together by the teeth 31 and being also curved upwardly 20 by the teeth 31, will form a most rigid connection, which at the same time will be readily dismantled or assembled by the ordinary wearer of such assemblage.

Referring to the construction of Figs. 7 and 8, 25 the frame is of E form and has a cross bar 50 connecting the pairs of legs 35' and 36'. Each pair of legs 35'-36' is designed to receive a clip, as indicated in Fig. 8, and the clips abut at their side faces 16', as indicated best in Fig. 8. 30

The pivot 39' and the catch 40' of the pin 38' are mounted upon the loops 34'.

In operation the clips A' of Figs. 7 and 8 will be held in position in the same manner and with the same strength as in the embodiments shown 35 in Figs. 1 to 6.

It is obvious that other shapes and forms of frames with parallel arms may be provided, such as X-shaped, T-shaped, W-shaped frames, which are designed to engage the clip finding, which finding forms a runway or guideway for the frame and at the same time conceals the frame. Where the arms of the X-shaped, T-shaped or W-shaped frame are not split, they fit into runways or slideways on the back of the ornament members, 40 as for example shown in application Patent 2,120,215 and/or application Patent 2,198,558. Where the legs, however, are positioned in pairs, as in the present application, the ornament members may be inserted between the pairs of legs as 50 disclosed herein, with the abutting faces of the ornaments being so shaped as to have the flush contact indicated at 16 and 16'.

The legs 35 and 36 of Figs. 1 to 6 or 35' and 36' of Figs. 7 and 8 might be closed together and the 55 pivot mount 24 may be placed so as to straddle said legs or the legs 35 and 36 might be combined into single legs which are longitudinally slotted to give the necessary resiliency with the pivot mount 24 being on one or both sides of the combined 60 legs 35-36.

Also instead of using the jaw members D, it is possible to place bosses 19 and projecting elements 31 on the back of the ornament to engage the legs 35-36 of the frame, as shown in Figs. 65 6 and 7.

It also may be desirable in certain instances to provide frames, such as shown in Figs. 6 and 7, either to carry the pin and catch and also to carry the jaw member and in such case the pin 70 and catch frame B or B' may be substituted by the jaw member frame depending upon whether the device is to be utilized.

The invention, however, is not intended to be restricted to any particular construction or ar- 75

angement of clip brooch construction, or to any particular application of any such construction, or to any specific method of operation, or manner of use, or to any of various details thereof, herein 5 shown and described, as the same may be modified in various particulars or be applied in many varied relations without departing from the spirit and scope of the claimed invention, the practical embodiments herein illustrated and described merely 10 showing some of the various features entering into the application of the invention.

What is claimed is:

1. In a clip brooch construction, at least one clip and a frame, said clip including an ornament 15 having a longitudinal axis and a toothed jaw member provided with a pivotal mount on the back of said ornament adjacent one side thereof and the axis of said pivotal mount being transverse to said longitudinal axis, said frame having 20 a transverse bar and at least one pair of parallel legs extending transversely outwardly therefrom, said legs being parallel to said longitudinal axis, said frame carrying a pin and catch, said pair of legs being inserted between said ornament and 25 said jaw member, said pair of legs embracing and frictionally grasping said pivotal mount adjacent said transverse bar and means carried by said jaw member to embrace and frictionally grasp the outside edges of said pair adjacent the outside 30 ends of the legs of said pair, the pivotal and said last mentioned means with the jaw member closed forming parallel slideways into which said legs are frictionally inserted, said frame including two pairs of legs and all said legs being on one 35 side of said transverse bar.

2. In a clip brooch construction, at least one clip and a frame, said clip including an ornament having a longitudinal axis and a toothed jaw member provided with a pivotal mount on the 40 back of said ornament adjacent one side thereof and the axis of said pivotal mount being transverse to said longitudinal axis, said frame having a transverse bar and at least one pair of parallel legs extending transversely outwardly therefrom, 45 said legs being parallel to said longitudinal axis, said frame carrying a pin and catch, said pair of legs being inserted between said ornament and said jaw member, said pair of legs embracing and frictionally grasping said pivotal mount adjacent 50 said transverse bar and provided with camming projections adjacent said outer ends and means carried by said jaw member to embrace and frictionally grasp the outside edges of said pair adjacent the outside 55 ends of the legs of said pair, the pivotal and said last mentioned means with the jaw member closed forming parallel slideways into which said legs are frictionally inserted, said pivotal mount including a low boss and a high boss and said transverse bar having an offset portion to fit over said low boss and to abut said high boss.

said last mentioned means including slotted transversely grooved teeth positioned on each side of said jaw member.

3. In a clip brooch construction, at least one clip and a frame, said clip including an ornament 5 having a longitudinal axis and a toothed jaw member provided with a pivotal mount on the back of said ornament adjacent one side thereof and the axis of said pivotal mount being transverse to said longitudinal axis, said frame having 10 a transverse bar and at least one pair of parallel legs extending transversely outwardly therefrom, said legs being parallel to said longitudinal axis, said frame carrying a pin and catch, said pair of legs being inserted between said ornament and 15 said jaw member, said pair of legs embracing and frictionally grasping said pivotal mount adjacent said transverse bar and provided with camming projections adjacent said outer ends and means carried by said jaw member to embrace and frictionally grasp the outside edges of said pair adjacent the outside 20 ends of the legs of said pair, the pivotal and said last mentioned means with the jaw member closed forming parallel slideways into which said legs are frictionally inserted with 25 said jaw member closed against said member, said frame being capable of withdrawal from said clip brooch without movement of said jaw member, said last mentioned means including slotted teeth positioned on each side of said jaw member, the 30 lower portions of said teeth being offset inwardly and said legs being curved away from said ornament and toward said jaw member upon being inserted between said slotted teeth.

4. In a clip brooch construction, at least one 35 clip and a frame, said clip including an ornament having a longitudinal axis and a toothed jaw member provided with a pivotal mount on the back of said ornament adjacent one side thereof and the axis of said pivotal mount being transverse to said longitudinal axis, said frame having 40 a transverse bar and at least one pair of parallel legs extending transversely outwardly therefrom, said legs being parallel to said longitudinal axis, said frame carrying a pin and catch, said pair of legs being inserted between said ornament and 45 said jaw member, said pair of legs embracing and frictionally grasping said pivotal mount adjacent said transverse bar and means carried by said jaw member to embrace and frictionally grasp the outside edges of said pair adjacent the outside 50 ends of the legs of said pair, the pivotal and said last mentioned means with the jaw member closed forming parallel slideways into which said legs are frictionally inserted, said pivotal mount including a low boss and a high boss and said transverse bar having an offset portion to fit over said 55 low boss and to abut said high boss.
